PUMP

John T. Hayden, Big Spring, Tex.

Application August 5, 1935, Serial No. 34,751

1 Claim. (Cl. 103—185)

This invention relates to pumps lifting fluid from wells either deep or shallow wells, and works on both up and down strokes. The invention consists of novel features and parts and combinations of the same as will be described hereinafter and then pointed out in the claim.

A practical embodiment of the invention is represented in the accompanying drawing, forming a part of this specification, in which characters of reference indicate corresponding parts in all the views.

Figure 1 is a sectional side elevation of the improvement. Figure 2 is a longitudinal section of the inlet valves shown in Figure 1. Figure 3 is a plan view of the valve cage shown in Figure 1. Figure 4 is a horizontal section of the valve cage.

The improved pump has upper and lower tubing sections 1 and 2, respectively, connected together by a center coupling ring 3. The center coupling ring (3) is provided with a tapered seat (4). A longitudinal outlet passage (5) provides fluid connection between said tubing—sections 1 and 2—and a lateral inlet passage (6) allows fluid communication between the well fluid outside the ring (3) and an intermediate portion of the tapered seat (4). A lower barrel (7) is attached to center ring (3) below said tapered seat (4) and extends and opens into said lower tubing section (2). An upper working barrel (8) is attached to said ring (3) above said tapered seat (4) and extends and opens into said upper tubing section (1). An axially bored tapered valve cage (9) is fitted into said tapered seat (4) and is provided with upper and lower inlet valve ports (10), communicating with said lateral inlet passage (6) and with the respective working barrels. A spool shaped inlet valve member (11) is slidably arranged in the bore of said cage and adapted to alternately close said valve ports. A lower traveling valve (12) is positioned in said lower barrel to permit downward flow only of fluid therethrough. An upper traveling valve (13) is positioned in said upper working barrel to permit upward flow only of fluid therethrough. A connecting rod (14) for said traveling valves passes through said spool shaped inlet valve member and a sucker rod (14a) is secured to the upper traveling valve to reciprocate said traveling valves. Spiders (15 and 16) attached to the bottom and top of the working barrels are fitted to the inside of the casing to

prevent vibration of working barrels. The lower end of the lower working barrel is fitted with a check valve (17), seating on a suitable valve seat on spider 15. This valve does not have anything to do with the working of pump but is provided to prevent loss of fluid in the column in case either the cups or the valve in the lower traveling valve becomes badly worn as the spool shaped sliding valve can only close one set of ports 10, which will invariably be the top set.

Thus, from the foregoing, it can be seen that a very simple and effective double stroke pump is provided which works equally well in deep or shallow wells and is composed of few parts and by having the tapered valve seat cage, can be rodded and repaired without disturbing the tubing in the well. Various changes may be made in the manufacture of this pump without departing from the principle thereof. Hence, I consider myself entitled to all such variations as come within the scope of the claim. Having thus fully described my invention, I claim as new and desire to secure by Letters Patent:

In a well pump, an upper and a lower tubing section; a coupling ring joining adjacent ends of said tubing sections and provided with a central tapered seat, a longitudinal outlet passage establishing fluid communication between said tubing sections and a lateral inlet passage establishing fluid communications between the well fluid outside the ring and an intermediate portion of the tapered seat; a lower working barrel attached to said ring below said tapered seat and extending and opening into said lower tubing section; an upper working barrel attached to said ring, above said seat and extending and opening into said upper tubing section; an axially bored tapered valve cage fitted in said tapered seat and provided with upper and lower inlet valve ports communicating with said lateral inlet passage to respective working barrels; a spool-shaped inlet valve member slidably arranged in the bore of said cage and adapted to alternately close said valve ports; a lower traveling valve arranged in said lower barrel to permit downward flow only of fluid therethrough; an upper traveling valve arranged in said upper barrel to permit upward flow only of fluid therethrough; a connecting rod for said traveling valves passing through said spool shaped inlet valve member and means for reciprocating said traveling valves.

JOHN T. HAYDEN.
